[57] **ABSTRACT**

An electroacoustic transducer comprising a thin-walled cylindrical sleeve with a vibrating diaphragm that includes at least one layer of piezoelectric material and rigidly secured at its peripheral edge to one end of the sleeve. This allows the diaphragm to perform a pivotal movement at its peripheral edge. In a second embodiment the sleeve is conical with the narrow end flanged inwardly and the diaphragm rigidly secured thereto. If the sleeve is metal, an integrated amplifier may be mounted thereon so that the sleeve acts as a heat sink.

ELECTROACOUSTIC TRANSDUCER HAVING A DIAPHRAGM MADE OF AT LEAST ONE LAYER OF PIEZOELECTRIC MATERIAL

The present invention relates to a transducer for converting acoustic vibrations into electric oscillations, and vice versa, in the form of a diaphragm with at least one layer of a piezo-electric material, the edge of the diaphragm being supported by a frame. Such transducers are particularly suitable for built-in use in a microphone.

It is known to use a transducer having a diaphragm which is divided into a plurality of elements. These elements are flexibly supported by a frame. In the embodiment of a microphone this frame is the microphone casing or a part thereof.

The invention is characterized in that the frame is a thin-walled sleeve, one end of which is rigidly secured to the edge of the diaphragm. This provides the advantage that the edge of the diaphragm is incapable of vibrating at right angles to its plane but it is capable of pivotal movement.

An embodiment of the invention is characterized in that the edge of the diaphragm along its periphery is secured to the inner surface of the end of the sleeve. In this embodiment, the diaphragm is secured with a tight fit in the sleeve by means of an adhesive, for example, glue.

Another embodiment is characterized in that the sleeve is conical and in that at the end having the smaller transverse dimensions its edge is flanged inwardly, the diaphragm being secured along its periphery to the flange. In this case also, securing may be by means of glue.

For satisfactory pivotal movement of the diaphragm it has proved of advantage for the outer dimensions of the flanged edge to be slightly smaller than those of the diaphragm.

The sleeve may be made of a synthetic resin or of a metal. In the latter case its wall thickness will be smaller. When the sleeve is made of metal, for example, brass, it is particularly advantageous for the amplifier associated with the transducer to be provided on the sleeve in the form of an integrated circuit. The sleeve then also serves as a heat sink for the energy dissipated in the integrated amplifier. The electrodes of the transducer then are directly connected to the contacts of the integrated amplifier. When the transducer is provided with an integrated amplifier on its frame, it may take the form of a built-in element for a microphone, and this facilitates, and saves time in, the assembly of the microphone.

The invention will now be described more fully with reference to the drawing, in which

FIG. 1 is a cross-sectional view of a cylindrical diaphragm secured in a cylindrical sleeve,

FIG. 2 is a plan view thereof,

FIGS. 3 and 4 are a cross-sectional view and a plan view respectively of the frame in the shape of a conical sleeve according to the invention, and

FIG. 5 shows a detail of this conical sleeve provided with an integrated amplifier.

In the Figures, a transducer 1 of circular shape comprises two layers 2 and 3 of a piezo-electric material the outer surfaces of which are each provided with a metal electrode 4 and 5, respectively, provided by deposition from vapor. In FIGS. 1 and 2, the transducer 1 is ce-

mented with a close fit in an end 8 of a cylindrical sleeve 6 the wall thickness of which is less than the thickness of the transducer 1. The other end 9 of the sleeve 6 is cemented to a fixed base 7. For use as a microphone, good results have been obtained with a transducer of diameter 15 mm and thickness about 300 μm and a tube wall thickness of about 40 μm .

For use as a microphone it has further proved of advantage for the transducer 1 of the form shown in FIG. 10 to be arranged, as shown in FIG. 3, on a conical thin-walled sleeve 10, which at its upper end 13, i.e., the end the transverse dimensions of which are smaller, has an inwardly flanged edge 12. On this flanged edge the transducer 1 is secured by means of cement. The other end 14 of the sleeve 10 is flanged outwardly, and the flanged edge 15 is secured to a fixed base 16.

Using a transducer of the specified kind, good results have been obtained with a sleeve having a wall thickness of about 100 μm .

FIG. 5 shows an integrated amplifier 20 which, by means of a metal base plate 21, is secured to the inner surface of the conical sleeve 10. The integrated amplifier is provided with a number of contact areas which, by means of short connecting leads, are connected to contacts 22 to 25 arranged in the conical sleeve 10 around the integrated amplifier. The electrode 4 is connected to the contact 22, for example, by means of a conductor deposited from vapor. The electrode 5 is connected to one of the remaining contacts through the metal sleeve 10.

What is claimed is:

1. An electroacoustic transducer comprising a thin-walled housing sleeve, a vibrating diaphragm including at least one layer of piezoelectric material, the wall thickness of the sleeve being less than the thickness of the diaphragm, and means for rigidly securing the outer peripheral edge of the diaphragm directly to the inner surface of one end of said thin-walled sleeve so that the peripheral edge of the diaphragm performs a pivotal movement.

2. An electroacoustic transducer comprising a thin-walled housing sleeve, the sleeve comprising a conical member with the smaller diameter end having its edge flanged inwardly a vibrating diaphragm including at least one layer of a piezoelectric material, means for rigidly securing the peripheral edge of the diaphragm to the flange so that the peripheral edge of the diaphragm performs a pivotal movement.

3. A transducer as claimed in claim 2, characterized in that the outer dimensions of the sleeve at the area of engagement of the flange with the diaphragm are slightly smaller than the outer dimension of the diaphragm.

4. A transducer as claimed in claim 2 wherein the wall thickness of the flange in the axial direction is less than the thickness of the diaphragm in said axial direction.

5. An electroacoustic transducer comprising a thin-walled housing sleeve made of metal, a vibrating diaphragm including at least one layer of a piezoelectric material, means for rigidly securing the peripheral edge of the diaphragm to one end of said thin-walled sleeve so that the peripheral edge of the diaphragm performs a pivotal movement, and an amplifier for the transducer signals mounted on the sleeve in the form of an integrated circuit.

6. An electroacoustic transducer comprising a thin-walled housing sleeve, the sleeve comprising a conical member with the smaller diameter end flanged inwardly from the inner surface of the sleeve, a vibrating diaphragm including at least one layer of a piezoelectric material, means for rigidly securing the peripheral edge of the diaphragm to the flange so as to extend radially beyond the outer surface of the sleeve at said

smaller end whereby the peripheral edge of the diaphragm performs a pivotal movement.

7. A transducer as claimed in claim 6 wherein the peripheral edge of the diaphragm is rigidly secured to the flange by engagement of one surface only of the diaphragm.
